US00D862031S

(12) **United States Design Patent** (10) Patent No.: **US D862,031 S**
(45) Date of Patent: **** Oct. 8, 2019**

(54) **FOOD PRODUCT**(71) Applicant: **Mars, Incorporated**, McLean, VA (US)(72) Inventors: **Peter Sebastian Slusarczyk**, Nolensville, TN (US); **Tracey Dianne Ziener**, Chicago, IL (US); **Yijun Wang**, Mississauga (CA); **Francis S. Shields**, Nashville, TN (US)(73) Assignee: **Mars, Incorporated**, McLean, VA (US)(***) Term: **15 Years**(21) Appl. No.: **29/673,045**(22) Filed: **Dec. 11, 2018****Related U.S. Application Data**

(63) Continuation of application No. 12/163,684, filed on Jun. 27, 2008.
